D10-36. OR D 12,573 EX

DESIGN FOR A WATCH-CASE.

Design No. 12,573, dated November 15, 1881.

UNITED STATES PATENT OFFICE.

HENRY UNTERMAYER, OF NEW YORK, N. Y.

DESIGN FOR A WATCH-CASE.

SPECIFICATION forming part of Design No. 12,573, dated November 15, 1881.

Application filed September 14, 1881. Term of patent 14 years.

To all whom it may concern:

Be it known that I, HENRY UNTERMAYER, of New York, in the county and State of New York, have invented a Design for Watch-Cases, of which the following is a specification.

The design consists of a conventional representation of a shield inclosed within a wreath of flowers, leaves, &c., as shown in the accompanying photographic illustration. The shield and wreath are in relief and are applied to occupy the middle portion of the case or cases, their size being made to harmonize with the size of the case. The ground in rear of the shield may be covered with straight-line engine-turning; but this is not an essential part of the design, and serves only to enhance the effect. I have also been accustomed to employ other ornamental work to give a finish to the case or cases, as shown in the said photographic illustration; but this feature may

also be omitted, the design consisting, as hereinbefore recited, of the shield and wreath occupying the central or middle part of the case.

The circular line of beaded work supplemented above and below by scroll-work shown in the accompanying photographic illustration is not sought to be protected herein, but has been made the subject of a separate application of even date herewith.

What I claim as my invention, and desire to secure by Letters Patent, is—

A design for a watch-case, substantially as shown and described.

Witness my hand this 12th day of September, A. D. 1881.

HENRY UNTERMAYER.

Witnesses:

CHAS. C. GILL,
HERMAN GUSTOW.
